UNITED STATES PATENT OFFICE.

WILLIAM McCONWAY, JR., AND WILLIAM J. REGAN, OF PITTSBURGH, PENNSYLVANIA,
ASSIGNORS TO THE McCONWAY & TORLEY COMPANY, OF PITTSBURGH, PENNSYLVANIA, A CORPORATION OF PENNSYLVANIA.

UNCOUPLING MECHANISM.

1,226,092.

Specification of Letters Patent. Patented May 15, 1917.

Application filed December 21, 1916. Serial No. 138,229.

To all whom it may concern:

Be it known that we, WILLIAM McCONWAY, Jr., and WILLIAM J. REGAN, citizens of the United States, residing at Pittsburgh, in the county of Allegheny and State of Pennsylvania, have invented certain new and useful Improvements in Uncoupling Mechanism; and we do hereby declare the following to be a full, clear, and exact description 10 of the invention, such as will enable others skilled in the art to which it appertains to make and use the same.

Our invention relates to uncoupling mechanism for actuating the locking device of a 15 car coupler, and while it is primarily designed to afford means especially suitable for use with couplers having locks that project downwardly through the coupler head or are actuated from beneath the same, yet 20 mechanism constructed in accordance with our invention may be advantageously employed in conjunction with couplers in which the locking devices project upwardly through or are accessible from above the 25 coupler head.

It is the object of the invention to provide uncoupling mechanism which is simple, strong, easily manipulated, and easily assembled and disassembled. Generally stated, 30 we are enabled to accomplish this object by employing for the purpose of moving the coupler lock to unlocked position means involving a plurality of pivotally connected members one of which is pivotally mounted 35 on a stationary part of the car, said members being maintained in assembled relation by a rotatable uncoupling lever which extends in a direction transversely of the car and which forms the pivotal connection 40 between the said pivotally connected members.

In the drawings illustrating our invention, the scope whereof is pointed out in the claims,

45 Figure 1 is a plan view of an uncoupling mechanism embodying our invention, showing its preferred relation to the coupler and car body.

Fig. 2 is a front elevation of the structures shown in Fig. 1, the coupler head being omitted.

Fig. 3 is a detail side elevation of the devices illustrated in Figs. 1 and 2.

Fig. 4 is a detail view, partly in central

section and partly in plan, of a portion of 55 the mechanism.

Fig. 5 is a section on the line 5—5, Fig. 3.

Fig. 6 is a section on the line 6—6, Fig. 4; and

Fig. 7 is a section on the line 7—7, Fig. 2. 60

We will now proceed to describe our invention more fully, so that others skilled in the art to which it appertains may apply the same.

In the drawings, 1 indicates a portion of 65 the end of a car, and 2 indicates a car coupler having a lock 3 by which the outward rotation of the coupler knuckle 4 is restrained. The details of construction of the coupler, its knuckle and knuckle locking device, not being essential features of our invention, may be of any desired or well-known form. As shown, the coupler is, however, preferably of a form wherein the lock 3 thereof projects downwardly outside of 70 75 the coupler head.

As the invention is especially suitable for the unlocking of car couplers which are mounted on cars so as to be capable of a lateral swinging or shifting movement when 80 the cars to which they are applied pass around curves in the track, the carry-iron 5 by which the coupler 2 is supported is, as shown, preferably of a form permitting such lateral movement of the coupler. Bolts 6, 6 85 and 7, 7 serve to securely connect the carry-iron to the car body.

The devices by which the coupler lock 3 is moved to unlocked position are supported by the carry-iron 5 which, for such purpose, 90 is preferably provided with separated bearings formed as downwardly extending hooks 8 that open toward the rear. Journaled in the hook-like bearings 8 so as to swing in the direction of length of the car is a member 9 95 to which is pivotally connected a vertically movable actuating arm or lever 10 that is operatively connected at its forward end to the coupler lock 3. The member 9 is provided with oppositely extending pintles or 100 journals 11 which rest in the bearings 8; and it is preferably also formed with a forwardly opening recess or socket 12 that is adapted to receive the inner end of the arm or lever 10, the walls of said recess, as shown 105 in dotted lines in Fig. 6, being preferably curved or rounded to conform to the shape of the adjacent end of the member 10. Pro-

jecting laterally from opposite sides of the pivoted member 9 are lugs 13 which extend beneath the hook-like brackets 8 and prevent the said member 9 from moving upwardly and thus becoming disassociated from the hooks 8, as will be readily understood from an inspection of Figs. 3 and 5. At its lower end the member 9 is provided with a shelf or bar 14 which is adapted to form a seat or support for the inner end of a rotatable uncoupling lever 15 that extends outwardly from the coupler toward the side of the car. The inner end 16 of the lever 15 extends upwardly so as to pass through corresponding openings in the members 9 and 10 and form a pivotal connection for said members.

The uncoupling lever 15, which is provided with a suitable operating handle 17, is preferably supported at its outer end by means of a rearwardly opening bracket 18 that is rigidly secured to the car 1, a cotter 19 being conveniently employed to prevent the escape of the uncoupling lever from the bracket.

The forward or outer end of the pivoted lock-actuating member 10 may be provided with an eye 20 for forming a pivotal connection with a link or bar 21 having a finger 22 that extends into a suitable slot 23 in the lower end of the coupler lock 3. While this form of connection between the lever 10 and the coupler lock is preferred, since it permits free action of the coupler under draft and buffing and allows for lateral play of the coupler without twisting the link or connection 21, it is, of course, to be understood that it is not an essential feature of our invention and that the form of connection may be adapted to the special requirements of such forms of couplers as may be used.

In assembling the mechanism the member 9 is turned to an approximately horizontal position so as to permit the trunnions 11 thereof to be positioned in the hook-like bearing brackets 8 of the carry-iron. The member 9 is then rotated downwardly to normal position and the rear end of the pivoted arm or lever 10, which has been operatively connected to the coupler lock 3 by the link 21, is inserted in the socket 12 of the member. This having been done the uncoupling lever 15 is held longitudinally of the car and lifted until its upturned end or pivot 16 enters the corresponding aligned pivot openings in the members 9 and 10. The uncoupling rod 15 is thereafter turned horizontally until its inner end rests upon the ledge or shelf 14 and its outer end is in assembled relation with the bracket 18. The assembling of the mechanism is then completed by putting the retaining cotter 19 in place. When assembled the parts are interlocked and the mechanism cannot become disconnected from the carry-iron, for the upturned end 16 of the uncoupling lever 15

prevents the escape of the pivoted member 10 from the socket of the member 9, while the lugs 13 upon the latter, together with the lever 10 when connected to the coupler lock, serve to prevent the escape of the pivoted member 9 from the supporting brackets 8 of the carry-iron 5.

The mode of operation of the mechanism will be readily understood by those skilled in the art. When the trainman grasps the handle 17 and rotates the uncoupling lever 15 the members 9 and 10 are swung upwardly, turning upon the pintles 11 and lifting the coupler lock 3 through the intermediary of the connecting member 21.

We claim:

1. In an uncoupling mechanism, the combination with a coupler, its lock, and carry-iron, of means for moving said lock to unlocked position, said means involving a member operatively connected to said lock and supported on said carry-iron so as to be rotatable only, said rotation being performed about a plurality of axes.

2. In an uncoupling mechanism, the combination with a coupler, its lock, and carry-iron, of means for moving said lock to unlocked position, said means involving a plurality of members which are pivotally supported by said carry-iron and which are connected with each other by a vertical pivot.

3. In an uncoupling mechanism, the combination with a coupler and its lock, of means for moving said lock to unlocked position, said means involving a member pivotally connected to the car, a lever pivotally connected to said last named member and operatively connected to said lock, and a rotatable uncoupling lever for actuating said pivotally connected members.

4. In an uncoupling mechanism, the combination with a coupler, its lock, and carry-iron, of means for moving said lock to unlocked position, said means involving a plurality of movably connected members supported by said carry-iron independently of said lock.

5. In an uncoupling mechanism, the combination with a coupler, and its lock, of means for moving said lock to unlocked position, said means involving a plurality of pivotally connected members one of which is pivotally mounted on a stationary part of the car and a rotatable uncoupling lever having a portion forming the pivotal connection of said pivotally connected members.

6. In an uncoupling mechanism, the combination with a laterally movable coupler, of a carry-iron therefor permitting said coupler to shift laterally, and a plurality of pivotally connected levers constituting means for actuating the lock of said coupler to cause it to assume an unlocked position, said carry-iron being provided with means for supporting said lock actuating means.

7. In an uncoupling mechanism, the combination with a coupler, and its lock, of a socketed member having pintles whereby it may be pivotally connected to the car, a member operatively connected to said lock and extending into the socket of said socketed member, and an uncoupling lever extend-

ing toward the side of the car and serving to maintain said last named members in assembled relation.

In testimony whereof we affix our signatures.

WILLIAM McCONWAY, Jr.
WILLIAM J. REGAN.
